(57) **CLAIM**

The ornamental design for a hammock bag, as shown and described.

DESCRIPTION

FIG. 1 is a front perspective view of a hammock bag showing my new design;

FIG. 2 is a rear perspective view thereof;

FIG. 3 is a top perspective view thereof;

FIG. 4 is a bottom perspective view thereof;

FIG. 5 is a front perspective view thereof shown in an alternate and partially closed position; and,

FIG. 6 is a front perspective view thereof shown in an alternate and open position.

The broken line showings of a hammock bag in FIGS. 1-6 are for the purpose of illustrating the environment in which the design is associated and form no part of the claimed design.
